UNITED STATES PATENT OFFICE.

GYULA KOESIS AND CHARLES BALAZS, OF ST. CLAIRSVILLE, OHIO.

WRENCH.

1,032,145.

Specification of Letters Patent.

Patented July 9, 1912.

Application filed February 9, 1912. Serial No. 676,584.

To all whom it may concern:

Be it known that we, GYULA KOESIS and CHARLES BALAZS, subjects of the King of Hungary, residing at St. Clairsville, in the county of Belmont and State of Ohio, have invented certain new and useful Improvements in Wrenches, of which the following is a specification, reference being had thereto in the accompanying drawing.

10 This invention relates to wrenches, and the objects of our invention are to provide a quick acting wrench wherein simple and effective means are employed, as will be hereinafter set forth, for rapidly adjusting 15 the wrench, and to provide a wrench with an adjustable handle that permits of different degrees of leverage being obtained.

Further objects of our invention are to provide a strong and durable nut wrench, 20 and to accomplish the above results by a wrench that is simple, inexpensive to manufacture, easy to manipulate and highly efficient for the purposes for which it is intended.

25 With the above and other objects in view, the invention resides in the novel construction, combination and arrangement of parts to be hereinafter specifically described and then claimed.

30 Reference will now be had to the drawing, wherein:

Figure 1 is a longitudinal sectional view of the wrench, Fig. 2 is a front elevation of the same, Fig. 3 is a horizontal sectional view taken on the line III—III of Fig. 1, Fig. 4 is a similar view taken on the line IV—IV of Fig. 1, and Fig. 5 is a similar view taken on the line V—V of Fig. 1.

A wrench in accordance with this invention 40 comprises a shank 1 rectangular in cross section and having the front side thereof provided with a longitudinal recess 2. The rear wall of the recess has a longitudinal slot 3 and one wall of the slot is provided with teeth 4. The outer end of the recess 2 is open and mounted upon in said recess is a block 5 and mounted upon the outer end of the shank is a fixed jaw 6, said jaw and said block being held by rivets 7 or other fastening means extending through 45 the walls of the recess 2. The jaw 6 presents a gripping surface 8 at the front side of the shank 1. The inner end of the shank 1 has a circular opening 9 and rotatably mounted in said opening is a bearing 10 having the inner end thereof enlarged and knurled,

as at 11, and the end of the bearing, within the recess thereof, is provided with a collar 12 that retains the bearing in the opening 9. The bearing 10 is cut away, as at 10^a to provide clearance for the teeth 14 of a rod 13.

Adjustably mounted in the nut 10 is the longitudinal rod 13 having one side thereof provided with teeth or threads 14 intermediate the ends thereof. The outer end of the rod is rotatably mounted in an opening 15 provided therefor in an adjustable jaw 16 slidably mounted upon the shank 1, said jaw having an opening 17 providing clearance for the rear and side walls of the shank 1. The jaw 16 presents a gripping surface 18 at the front side of the shank, said gripping surface co-operating with the gripping surface 8 when gripping a nut or other body. 75 The end of the rod 13, within the recess 2, has a radially disposed arm 19 that extends into the slot 3 and can be swung into engagement with the teeth 4 within said slot. Encircling the rod 13, between the nut 10 and the jaw 16, is a coiled compression spring 20 that shifts the jaw 16 toward the jaw 6 when the arm 19 is moved out of engagement with the teeth 4.

Slidably mounted upon the inner end of the rod 13 is a handle 20 having the ends thereof provided with ferrules or caps 21. The handle 20 has a longitudinal opening 22 and a longitudinal groove 23, said opening and said groove providing clearance for the rod 13 and the teeth 14 thereof. The handle 20 has a bearing 24 and fulcrumed in said bearing is a lever 25 that has one end thereof bent and toothed to extend through an opening 26 in the handle 20 and engage the teeth 14 of the rod 13. The opposite end of the lever 25 is pressed by a flat spring 27 secured to the handle 20 and engaging the inner side of said handle, said spring retaining the lever normally in engagement with the rod 13. The teeth 14 extending in the groove 23 prevents the handle 20 from rotating upon the rod 13, and by pressing upon the lever 25, the handle can be adjusted longitudinally of the rod. The closer the handle is to the inner end of the rod 13, the greater the leverage that can be obtained when using the wrench, and when it is not necessary to use a great degree of leverage to rotate a nut, the handle 20 can be locked 105 in proximity to the inner end of the shank. When the handle 20 is rotated, the rod 13

is shifted to move the arm 19 either into or out of engagement with the teeth 4, consequently the jaw 16 can be easily adjusted upon the shank 1. The block 5 permits of the adjustable jaw 16 being placed upon the shank and the parts of the wrench easily assembled.

It is thought that the operation and utility of the invention will be apparent without further description, and while in the drawing there is illustrated a preferred embodiment of the invention, it is to be understood that the structural elements are susceptible to such changes as fall within the scope of the appended claim.

What we claim is:—

A wrench comprising a shank having a longitudinal recess in the front side thereof, the rear wall of said shank having a longitudinal slot formed therein with one of the walls of said slot toothed, a fixed jaw car-

ried by the outer end of said shank, an adjustable jaw slidably mounted upon said shank and extending into the recess thereof, a toothed rod rotatably mounted in the inner end of said shank and rotatably mounted in said adjustable jaw, an arm carried by the outer end of said rod and extending into the slot of said shank to engage the toothed wall thereof, a coiled spring encircling said rod within the recess of said shank between said adjustable jaw and the inner end of said shank, and a handle carried by the inner end of said rod.

In testimony whereof we affix our signatures in the presence of two witnesses.

GYULA KOESIS.
CHARLES BALAZS.
